UNITED STATES PATENT OFFICE.

JEREMIAH J. FITZPATRICK, OF TULSA, OKLAHOMA.

PUMPING DEVICE FOR OIL WELLS.

Application filed November 24, 1923. Serial No. 676,799.

To all whom it may concern:

Be it known that I, JEREMIAH J. FITZPATRICK, a citizen of the United States, residing at Tulsa, in the county of Tulsa and State of Oklahoma, have invented certain new and useful Improvements in Pumping Devices for Oil Wells, of which the following is a specification.

This invention relates to pumping devices for oil wells, and more particularly to a combined jet flowing device and packer.

Many wells in the oil fields have an accumulation of gas sufficient to flow the oil without pumping but the flow under such conditions is frequently intermittent and irregular and when the gas pressure lowers, the flow ceases. To start the flow of oil again, it is necessary to employ artificial means, such as the usual type of pump.

An object of the present invention is the provision of a jet flow device which may be readily moved from inoperative to operative position and which is adapted to be attached intermediate in the well tubing at a distance above the ordinary working barrel at the bottom of the well.

A further object of the invention is the provision of a jet flowing device and packer by means of which water may be removed from the oil sand and the well restored to life, after which the device continues to operate as a tubing packer.

A further object of the invention is the provision of a packer which may be arranged in the tubing and which does not interfere with the operation of the usual type of mechanical pump.

In the accompanying drawings, I have shown one embodiment of the invention. In this showing:

Figure 1 is a front elevation,

Figure 2 is a central vertical sectional view,

Figure 3 is a transverse sectional view on line 3—3 of Figure 2,

Figure 4 is a similar view on line 4—4 of Figure 2, and,

Figure 5 is a detail view of a portion of the apparatus showing the locking means employed on the barrel.

Referring to the drawings, the reference numeral 1 designates a section of ordinary well tubing to which the device is adapted to be attached. A nipple 2 which is swaged or bell-shaped, is arranged on the lower end of the well tubing. As shown, the upper

end of the nipple is internally threaded to receive the external threads formed on the end of the tubing. A cylinder 3 is secured to the lower end of the nipple and the cylinder forms a housing for the flowing device. A bushing 4 is arranged in the lower end of the housing cylinder forming a partition separating the interior of cylinder 3 from the space below. This bushing is provided with a central aperture which is internally threaded to receive a section 5 of well tubing the upper end of which communicates with the interior of cylinder 3. The tubing extends downwardly through the apparatus and is provided with the usual working barrel and standing valve adjacent the bottom of the well. The packer is preferably arranged at about 20 feet above the working barrel of the well. The bushing is further provided with apertures 6 and nipples 7, having central openings, are arranged in these apertures. Ball valves 8 are arranged on the nipples and these ball valves are adapted to be covered by suitable crowns 9, having openings 10 therein for the passage of gas. The bushing is provided with a downwardly depending cylindrical portion 11, forming a gas header and a chamber 12 is provided thereby surrounding the well tubing 5. A tapering portion 13 is formed on the bottom of the gas header or bushing and this tapering portion is provided with openings 14 to permit gas and fluid to pass upwardly therethrough when the tubing is being lowered in the oil well. A cylinder 15 is secured to the bottom of the tapering portion 13 and this cylinder extends downwardly to receive the base of the packer. A stud or pin 16 is arranged on the exterior of the cylinder. A collar 17 is slidably arranged around the cylinder 15, and this collar is provided with a tapered inner wall 18, adapted to snugly receive the tapered lower portion 13 of the gas header.

A cylinder 19 is mounted on this collar and slidably surrounds the inner cylinder 15. The cylinder 19 is provided with a slot having a vertical portion 20, an upper horizontal portion 21, and a lower horizontal portion 22 for the reception of the pin 16. Steel springs 23 are arranged on the exterior of this cylinder and bowed outwardly, as shown. The outer bowed portion of these springs contact with the inner surface of the well casing (not shown).

Beneath the cylinder 19, a collar 24 is se-

cured to the inner cylinder 15 by means of screw threads. The lower portion of this collar is extended downwardly as a flange and a rubber or composite skirt or packing 26 is secured thereto by means of rivets 25. Resilient members 29 have their upper ends secured to the lower portion of the skirt 26 and extend downwardly therefrom to form a guide therefor.

10 The operation of the device is as follows: The apparatus is arranged in the well tubing and lowered until the anchor on the bottom of the well tubing strikes the bottom of the well. When the bottom is reached, 15 the tubing is raised slightly to allow the pin 16 to ride freely in the upper horizontal portion 21 of the slot in cylinder 19, when it is given a quarter turn to the left to bring the stud or pin 16 in alignment with the vertical portion 20 of the slot. The tubing is then lowered until the pin reaches the bottom of the aperture when it is again turned to lock the apparatus in closed position, closing the openings 14 and setting the 20 packer. The outer portion of the bow of springs 23 contact with the inner surface of the well casing and during the operation of setting the packer they hold cylinder 19 in a fixed position permitting the cylinder 15 to which pin 16 is attached to move freely both vertically and horizontally within the confines of slot in the cylinder 19. The rubber or rubber composite skirt 26 swells by contact with the oil on its being lowered 25 into the casing and after it is placed in position, gas pressure from beneath causes it to expand to form a gas-tight fit. It will be apparent from the foregoing description that during the process of locating the jet flow packer in an oil well that there is an open avenue for the fluid between the cylinder 15 and the tubing 5 with an outlet at the upper end through apertures 14, but after the packer is set and the apertures 14 are closed the gas pressure must operate 30 through the packer and the space between cylinder 15 and tubing 5 to the gas header or bushing 4 where it is directed through apertures 6, nipples 7 and ball valves 8 thence into tubing 1 where it produces the 35 jetting effect lifting the oil from below the working barrel, and always keeping the gas pressure off the well sand.

It is to be understood that the form of 40 the invention herewith shown and described is to be taken as a preferred example of the same, and that various changes in the shape, size, and arrangement of parts may be resorted to without departing from the spirit 45 of the invention or the scope of the subjoined claims.

Having thus described my invention, I claim:

1. In a jet flow packer for oil wells, a 50 housing adapted to be arranged at a dis-

tance from the bottom of the well, a partition extending transversely of said housing, well tubing depending from said partition forming a gas chamber within said housing beneath the partition, said partition being provided with openings for the passage of gas, the outer wall of said housing being provided with openings, and a member surrounding said housing and adapted to close said openings.

2. In a jet flow packer for oil wells, a housing adapted to be arranged at a distance from the bottom of the well, a partition extending transversely of said housing, well tubing depending from said partition forming a gas chamber within said housing beneath the partition, said partition being provided with openings for the passage of gas, the outer wall of said housing being provided with openings, a cylindrical member surrounding the lower portion of said housing, and a collar carried by said member and adapted to cover said openings.

3. In a jet flow packer for oil wells, a housing adapted to be arranged at a distance from the bottom of the well, a partition extending transversely of said housing, well tubing depending from said partition forming a gas chamber within said housing beneath the partition, said partition being provided with openings for the passage of gas, the outer wall of said housing being provided with openings, a cylindrical member carried by said housing and surrounding it, said cylindrical member being provided with a slot, a pin arranged on said housing, and a collar arranged on the upper end of said cylindrical member and adapted to close said openings when said pin is in the upper portion of said slot.

4. In a jet flow packer for oil wells, a housing adapted to be arranged at a distance from the bottom of the well, said housing being provided with a gas chamber, the wall of said housing being provided with openings to admit gas to said chamber, means for closing said openings, and a rubber skirt arranged exteriorly of said housing beneath said openings.

5. In a jet flow packer for oil wells, a housing adapted to be arranged at a distance from the bottom of the well, said housing being provided with a gas chamber, the wall of said housing being provided with openings to admit gas to said chamber, means for closing said openings, a rubber skirt arranged exteriorly of said housing beneath said openings, and a wire cage surrounding said skirt.

6. A packer for oil wells comprising a cylindrical supporting member, an outwardly flaring cup of flexible material secured to the bottom of said supporting member and depending therefrom, and a plurality of resilient members having their

upper ends secured to said cup and depending beneath said cup.

7. A packer for oil wells comprising a cylindrical supporting member, an outwardly flaring cup of flexible material secured to the bottom of said supporting member and depending therefrom, and a plurality of resilient members having their upper ends secured to said cup and depend-

ing beneath said cup, the lower ends of said resilient members being extended inwardly. 10

In testimony whereof, I affix my signature in presence of two witnesses.

JEREMIAH J. FITZPATRICK.
